UNITED STATES PATENT OFFICE.

JAMES V. THOMPSON, OF FORT MADISON, IOWA.

CARTRIDGE-LOADER.

SPECIFICATION forming part of Letters Patent No. 395,858, dated January 8, 1889.

Application filed October 9, 1888. Serial No. 287,687. (No model.)

To all whom it may concern:

Be it known that I, JAMES V. THOMPSON, of Fort Madison, in the county of Lee and State of Iowa, have invented a new and Improved 5 Cartridge-Loader, of which the following is a full, clear, and exact description.

My invention relates to an improvement in cartridge-loaders, and has for its object to provide a machine of simple and durable construction and which may be expeditiously and 10 conveniently manipulated without danger of exploding the primer.

The invention consists in the construction and combination of the several parts, as will 15 be hereinafter fully set forth, and pointed out in the claims.

Reference is to be had to the accompanying drawings, forming a part of this specification, in which similar letters of reference indicate 20 corresponding parts in all the figures.

Figure 1 is a front elevation of the machine partly in section. Fig. 2 is a plan view, with the covers of the various receptacles open; and Fig. 3 is a detail section of the filling cup and 25 tube.

In carrying out the invention, A represents a base of any suitable construction, and B a T-standard attached to the base, preferably near one end, at the back. Upon the extremities of the horizontal member of the standard B a threaded lug, b, is formed, and upon said lugs a powder and a shot magazine, C and C', are respectively secured. The magazines are 30 preferably cylindrical in contour, and provided with a hinged top, d, and an interiorly-threaded collar, d', upon the bottom, purposed to receive the threaded lugs b. Within each magazine, preferably at one side near the top, a bar, d'', is attached, whereby the 35 powder or shot in the graduate employed may be evened off by passing the said graduate beneath the said bar. The top d is slotted in the flange to receive the bar. About the center of the base a second standard, D, is projected upward, having at or near the center two horizontal arms, e e', extending in opposite directions. The one, e, which passes in front of one magazine, terminates opposite the space intervening the two magazines in a 40 vertical sleeve, e'', preferably provided with two perpendicular bores, e''' and e'''. 45

In the upper end of the standard D one end

of a lever, E, is pivoted, the pivotal pin passing through a longitudinal slot in the said lever, as best shown in Fig. 1. The pivotal 55 end of the lever and the horizontal arm e' of the standard D are connected by a spiral or coil spring, E'. A rod, F, is pivoted to the said lever at or near the center of the same, which rod passes through the bore e''' of the 60 sleeve e'', and is provided at the lower end with a head, F', of a contour and size to neatly fit into a cartridge-shell.

A short standard, G, is secured to the base at one side of the main standard D, upon 65 which an angled arm, H, is held to slide, being guided by a rib, g, formed at one side edge of the standard, as best shown in Fig. 2.

The vertical member of the angled arm is 70 slotted and adjustably held in connection with the standard by a set-screw, g'. At the extremity of the horizontal member of the angled arm H a cup, H', is formed, provided with a vertical bore, h, extending from top to 75 bottom, the upper half of the said bore being tapering, as best shown in Fig. 3. The cup H' is also provided with a rabbet, h', in the bottom, and a spout or side projection, h'', open at the top. The spout or projection h'' 80 is adapted to receive the lower end of a filling-tube, H'', which tube extends vertically upward through the bore e''' of the sleeve e'', and is flared outward at the upper end to provide a funnel-mouth, H''. 85

Beneath the cup H' a metal disk, K, is secured to the base, provided with a centrally-embedded elastic cushion, having a central opening, k, therein, which opening registers with a similar opening, k', produced in and 90 extending through the base, as illustrated in Fig. 1.

Upon the disk K, at one side of the cushion, a vertical semicircular spring, k'', is attached, having preferably outwardly-flaring ends. 95

A lidded wad-box, M, is secured to the base at or near one end, preferably divided into two compartments by a transverse partition, m. An extractor, M', adapted to grasp the head of the shell, is secured to the base at 100 any suitable point, and the said base is fixedly held upon any desired support by a clamp, N.

In operation the cup H' is elevated and the

open edge of the shell N' introduced therein at the bottom. The head of the shell is then made to rest upon the cushion, the primer being over the aperture in said cushion, and the 5 cup is adjusted to a contact with the shell. If the shell is made of paper, before being introduced into the cup it is jacketed in a metal casing, N². The powder is taken from the receptacle by any suitable graduate and the 10 surplus is removed by passing the top of the graduate under and in contact with the bar d². The powder is emptied into the filling-tube, from whence it passes through the cup into the shell, a wad is introduced into the 15 cup and rammed down upon the powder by manipulating the lever E, and the shot and a second wad are introduced in the same manner. When a paper shell is used, the cap of the shell after being filled is introduced between the jaws of the extractor and thus held in a fixed position. The jacket may then be 20 readily slipped off.

It will be observed that by means of the construction of the loader it may be used in 25 any place where there is a support, and a clamp need not necessarily be employed; or, for instance, it may be placed upon the ground, upon a stump, in a boat, wagon, or upon a counter.

30 Cast-iron and glass are not used in the construction of the loader, as I propose to employ refined malleable iron, wrought-iron, and tin for the several parts and brass at any point where there is friction.

35 Having thus fully described my invention, I claim as new and desire to secure by Letters Patent—

1. The combination, with an essentially vertical standard, a horizontal arm projected

from the same, a vertical sleeve integral with 40 the said arm, and a spring-actuated lever pivoted in the top of said standard, of a plunger-carrying rod attached to the lever and reciprocating in said sleeve, a vertically-adjustable arm, a filling-cup attached to the arm, a disk 45 beneath the cup, and a cushion embedded in said disk, substantially as shown and described.

2. The combination, with an essentially vertical standard, a horizontal arm projected 50 from the same, a vertical sleeve integral with said arm, and a spring-actuated lever pivoted in said standard, of a plunger-carrying rod attached to the lever and reciprocating in said sleeve, a vertically-adjustable arm, a spouted 55 filling-cup attached to the arm, a filling-tube passing through the said sleeve into the cup, a disk beneath the cup, and an apertured elastic cushion embedded in said disk, substantially as shown and described.

3. The combination, with an essentially vertical standard, a horizontal arm projected from the same, a vertical sleeve integral with 60 said arm, a spring-actuated lever pivoted in said standard, and a detachable shot and powder magazine provided with a transverse scraper-bar, of a plunger-rod pivoted to the lever and reciprocating in said sleeve, a vertically-adjustable arm, a bottomless spouted cup attached to said arm, a filling-tube passing through the sleeve into the cup, a disk 65 beneath the cup, and an apertured elastic cushion embedded in said disk, substantially as shown and described.

JAS. V. THOMPSON.
